CLAIM

The ornamental design for an “low frequency generator device with nine tuning forks” as shown and described.

DESCRIPTION

FIG. 1 is a front right perspective view thereof;

FIG. 2 is a front perspective view thereof;

FIG. 3 is a back perspective view thereof;

FIG. 4 is a top perspective plan view of the thereof;

FIG. 5 is a bottom perspective plan view thereof;

FIG. 6 is a right side perspective view thereof; and,

FIG. 7 is a left side perspective view thereof.
